IGNITION SYSTEM

Anthony J. Di Lucci, Los Angeles, Calif., assignor
of one-half to Sydney J. Levy, Los Angeles,
Calif.

Application May 26, 1941, Serial No. 395,212

18 Claims. (Cl. 123—148)

My invention relates to internal combustion engines, and the object of the invention is to provide a novel ignition system for use in such engines.

A further object of the invention is to provide an ignition system for an internal combustion engine which uses high frequency discharges for the purpose of igniting the charge. Many attempts have been made to use high frequency in ignition systems, but many difficulties have been encountered in these attempts, and it is a further object of my invention to provide an ignition system using high frequency which will overcome the difficulties previously encountered.

Further objects and advantages will be made evident hereinafter.

Referring to the drawings which are for illustrative purposes only:

Fig. 1 is a vertical section through a portion of an internal combustion engine in which my ignition system has been installed, the piston being shown at its lowest position;

Fig. 2 is a section through the same engine on a plane at right angles to the plane of Fig. 1, the piston being shown in its upper position;

Fig. 3 is a section on a plane represented by the line 3—3 of Fig. 1;

Fig. 4 is a section on a plane represented by the line 4—4 of Fig. 1;

Fig. 5 is an exploded view showing the details of construction of one of the electrodes of the ignition system of the engine; and

Fig. 6 is a connection diagram of the system.

The invention is applied to any internal combustion engine of conventional construction in which 11 is a cylinder block having a cylindrical bore 12 in which a piston 13 reciprocates. This piston 13 has a wrist pin 14 which is engaged by the upper end of a connecting rod 15. The lower end of the connecting rod 15 is driven by a crank 16. The above parts or parts similar in construction are found in nearly all internal combustion engines as now constructed. These engines operate by drawing a charge of mixed fuel and air into the bore 12 through a fuel inlet 17 on the downstroke of the engine so that at the end of the ignition stroke with the parts in the position shown in Fig. 1 the cylindrical bore 12 is filled with a combustible gaseous mixture of fuel and air. As the piston is raised from the

position shown in Fig. 1 to the position shown in Fig. 2, this gas is compressed and at or near the top of the piston stroke the charge is ignited usually by an electrical discharge supplied to the mixture through a conventional pipe or spark

plug which is not used in the practice of my invention and is therefore not shown in the drawings.

In the practice of my invention the charge is ignited by a spark gap assembly 20, providing spark gaps between which discharges take place, the spark gap assembly 20 being carried on the top of and moving with the piston 13.

The spark gap assembly 20 may take various forms, but in the form shown it consists of three electrodes mounted on top of the piston, preferably aligned in a row disposed diametrically across the piston and comprising a central electrode 22 and two outer electrodes 21 and 22a. The electrode 21 is a block of metal threadedly secured in the piston head wall 40. The electrode 22a is of substantially the same construction as that of the electrode 22, which is described as follows.

As shown in Fig. 5, a threaded rod 41 is formed with an electric spark discharge head 42. It is disposed in an aperture 50 in the piston head wall 40 and is insulated therefrom by an insulating assembly comprising a metal washer 43 and a mica washer 44 arranged between the head 42 and the piston head wall 40, a mica bushing 45 concentrically between the rod 41 and the piston head wall 40, and a mica washer 46 and metal washer 47 below the piston head wall 40, the former being in contact with the lower surface of the piston head wall 40. The rod 41 is held in assembled relationship with the piston head wall 40 by means of a plurality of fins 48, each of which is provided with an axially elongated, internally threaded hub 49. These fins are successively threaded upon the rod 41, the first being drawn tightly against the metal washer 47, and the remaining fins being in turn drawn tightly one against the other. Preferably, the bore of the lowermost fin extends only part way therethrough, forming a socket for the reception of the lower end of the rod 41.

These fins act to transfer to and dissipate in the oil bath of the crankcase of the engine the heat generated at the spark gaps 23 and 23a. A similar construction may also be used for cooling the electrode 21. The fin construction serves to prevent preignition by keeping the temperature of the electrodes below that at which preignition occurs.

The charge is ignited by a high frequency discharge over the spark gaps 23 and 23a. For the purpose of producing this discharge, I utilize a high frequency transformer 24 which consists of a primary 25 and a secondary 26. The primary

23 consists of a few turns of relatively large diameter wire, and the secondary 26 consists of many turns of fine wire. Both the primary and the secondary are carried on insulating spools 27 and 28 respectively, the spool 27 which carries the primary being attached to the cylinder block 11 inside the crankcase in a position substantially as shown, that is, surrounding the connecting rod 15 and outside the bore 12. The spool 28 carrying the secondary 26 is fixed to and carried by the connecting rod 15 and is in the position shown in Fig. 1 when the connecting rod is down, and moves up inside the primary 25 when the connecting rod is in its upper position.

One terminal conductor 29 of the secondary 26 is secured in good electrical connection to the connecting rod 15 and the other terminal conductor 30 of the secondary is secured to but insulated from the connecting rod and is electrically connected as shown to the electrode 22a. The electrode 21 of the spark gap assembly is secured in electrical connection with the piston. Any potential induced in the secondary 26 causes a current to flow from the connecting rod 15 through the secondary 26, through the terminal wire 30, to the electrode 22a of the spark gap assembly 20, across the spark gap 23a to the central electrode 22, across the spark gap 23 to the electrode 21 and from the electrode 21 to the piston 13 and through the wrist pin 14 and connecting rod 15 back to its source. In other words, if a potential is impressed on the secondary 26, a spark gap is forced to pass across the spark gaps 23 and 23a if the potential is sufficiently high to cause the dielectric in the spark gaps to break down and allow the spark to pass.

For the purpose of inducing an electrical potential in the secondary 26, a high frequency potential is impressed on the primary 25. The primary 25 has two terminals 31 and 32, as indicated in the diagram, Fig. 6. The terminal 31 is connected to one terminal of a spark gap 33 which may be adjusted as to distance so that the voltage required to break it down may be regulated. The other terminal 32 is connected to one terminal of a charging secondary 34. The other terminal 35 of the secondary 34 is connected to the other side of the spark gap 33. Due to this arrangement if a potential is impressed on the secondary 34 a spark will jump across the gap 33 if the potential is sufficiently high.

Connected between the wires 32 and 35 is a condenser 36, the purpose of this condenser being to receive and store a charge of electricity and then discharge this charge across the gap 33 in a rapidly repeated cycle. The arrangement of condenser and spark gap is well understood in the art and the effect of it is to set up a rapidly oscillating or alternating current of high frequency through the primary 25 if the secondary 34 is properly energized. The secondary 34 is energized by a primary 37 which is fed with an oscillating or alternating current from a suitable generator 38. In some cases it may be desirable to place a distributor 39 in the circuit from the primary 37 for the purpose of causing impulses to occur at definite positions of the piston, the distributor 39 being geared to the engine to cause these impulses to occur at the proper intervals. This distributor may ordinarily be omitted, the device itself acting as a distributor due to the reciprocation of the connecting rod 15.

The method of operation of the invention is as follows.

is moving up and down and the secondary 26 is being drawn into the position shown in Fig. 2 and from there carried down into the position shown in Fig. 1, and then returned to its original position as the crankshaft 16 of the engine is rotated. With the coil 26 in the position shown in Fig. 1, the primary 25 has very little effect on the secondary 26 due to the fact that they are not close to each other. As the secondary 26 is thrown up inside the primary 25 the primary induces a potential in the secondary 26 due to the fact that the secondary is in an electro-magnetically linked position with the primary.

There is impressed on the primary 25 a high frequency oscillating or alternating potential which in turn induces a high frequency potential in the secondary 26. Due to the fact that the primary 25 has relatively few turns, it is supplied with a current of considerable amperage and a low voltage, and when a high frequency current flows in the primary 25 a high potential is induced in the secondary 26 due to the fact that the primary has only a few turns and the secondary 26 has very many turns. The voltage which is therefore impressed on the spark gaps 23 and 23a is a high frequency, high voltage potential which causes high voltage and high frequency discharges to take place across the spark gaps 23 and 23a. These high frequency, high potential discharges are very efficient in initiating combustion of an explosive mixture carried in the bore 12 above the piston 13.

It will be recognized by one skilled in the art that considerable variation may be made in the construction of the internal combustion engine shown in my drawings. In as far as this engine construction is concerned, the drawings may be considered to be largely diagrammatic and merely for the guidance of one skilled in the art of engine construction. In a somewhat similar manner the apparatus and procedure necessary to produce high voltage, high frequency discharges are also well understood in the art.

My invention consists broadly of producing a high voltage, high frequency discharge in the combustion space of an engine by spark gaps carried on the piston of the engine, the discharge being timed either by a distributor, such as the distributor 39, or by the position of the secondary 26 in the primary 25.

I claim as my invention:

1. In an ignition system for an internal combustion engine, the combination of: a piston closing, at its pressure end, a combustion space which may contain a combustible gas mixture; members carried by said piston in said space, said members being separated from each other to form a spark gap; and means for impressing on said spark gap, at the instant it is desired to explode said mixture, a high frequency alternating electromotive force.

2. In an ignition system for an internal combustion engine, the combination of: a piston closing, at its pressure end, a combustion space which may contain a combustible gas mixture; members carried by said piston in said space, said members being separated from each other to form a spark gap; a connection rod pivoted at one end on a wrist pin carried in said piston; a crank on which the other end of said connection rod is pivoted; a secondary winding or coil of wire carried by said connection rod and having its terminals so connected as to impress an electromotive force across said spark gap; a primary

winding or coil which is secured in fixed relationship to the space in which said piston reciprocates and which is so placed as to enable said coil to induce an electromotive force in said secondary as said piston approaches one end of its travel; and means for causing an electric current to flow in said primary winding.

3. In an ignition system for an internal combustion engine, the combination of: a piston closing, at its pressure end, a combustion space which may contain a combustible gas mixture; members carried by said piston in said space, said members being separated from each other to form a spark gap; a connection rod pivoted at one end on a wrist pin carried in said piston; a crank on which the other end of said connection rod is pivoted; a secondary winding or coil of wire carried by said connection rod and having its terminals so connected as to impress an electromotive force across said spark gap; a primary winding or coil which is secured in fixed relationship to the space in which said piston reciprocates and which is so placed as to enable said coil to induce an electromotive force in said secondary as said piston approaches one end of its travel; and means for causing a high frequency electric current to flow in said primary winding.

4. In an internal combustion engine, the combination of: two members so placed in the combustion space of said engine as to be separated by a spark gap; a secondary winding or coil connected to impress an electromotive force across said spark gap; a primary winding or coil so placed as to induce an electromotive force in said secondary winding, said coils being mutually movable with relation to each other and so moved in synchronism with the piston of the engine to vary the degree of induction between said coils; and means for passing an electric current through said primary winding.

5. In an internal combustion engine, the combination of: two members so placed in the combustion space of said engine as to be separated by a spark gap; a secondary winding or coil connected to impress an electromotive force across said spark gap; a primary winding or coil so placed as to induce an electromotive force in said secondary winding, said coils being mutually movable with relation to each other and so moved in synchronism with the piston of the engine to vary the degree of induction between said coils; and means for passing a high frequency alternating electric current through said primary winding.

6. In an internal combustion engine, the combination of: two members so placed in the combustion space of said engine as to be separated by a spark gap; a secondary winding or coil connected to impress an electromotive force across said spark gap; a primary winding or coil so placed as to induce an electromotive force in said secondary winding, said coils being mutually movable with relation to each other and so moved in synchronism with the piston of the engine to vary the degree of induction between said coils; and means for passing an electric current through said primary winding at the instant it is desired to ignite the charge of said engine.

7. In an internal combustion engine, the combination of: two members so placed in the combustion space of said engine as to be separated by a spark gap; a secondary winding or coil connected to impress an electromotive force across said spark gap; a primary winding or coil so placed as to induce an electromotive force in said

secondary winding, said coils being mutually movable with relation to each other and so moved in synchronism with the piston of the engine to vary the degree of induction between said coils; and means for passing a high frequency alternating electric current through said primary winding at the instant it is desired to ignite the charge of said engine.

8. An ignition system for an internal combustion engine having a piston reciprocating in a combustion space and means for periodically delivering a combustible gas mixture to said space, comprising: two members placed in said combustion space in such relationship as to form a spark gap therebetween; a secondary winding or coil connected to impress an electromotive force across said spark gap and so mounted as to reciprocate in synchronism with said piston; a primary winding or coil secured in a position which is fixed in relation to said combustion space and in which said secondary coil is brought into inducing relationship with said primary coil as said secondary coil approaches one end of its reciprocation; and means for passing an electric current through said primary coil.

9. An ignition system for an internal combustion engine having a piston reciprocating in a combustion space and means for periodically delivering a combustible gas mixture to said space, comprising: two members placed in said combustion space in such a relationship as to form a spark gap therebetween; a secondary winding or coil connected to impress an electromotive force across said spark gap and so mounted as to reciprocate in synchronism with said piston; a primary winding or coil secured in a position which is fixed to said combustion space and in which said secondary coil is brought into inducing relationship with said primary coil as said secondary coil approaches one end of its reciprocation; and means for passing a high frequency alternating electric current through said primary coil.

10. An ignition system for an internal combustion engine having a piston reciprocating in a combustion space and means for periodically delivering a combustible gas mixture to said space, comprising: two members placed in said combustion space in such relationship as to form a spark gap therebetween; a secondary winding or coil connected to impress an electromotive force across said spark gap and so mounted as to reciprocate in synchronism with said piston; a primary winding or coil secured in a position which is fixed in relation to said combustion space and in which said secondary coil is brought into inducing relationship with said primary coil as said secondary coil approaches one end of its reciprocation; and means for passing an electric current through said primary coil at the instant it is desired to ignite said mixture.

11. An ignition system for an internal combustion engine having a piston reciprocating in a combustion space and means for periodically delivering a combustible gas mixture to said space, comprising: two members placed in said combustion space in such relationship as to form a spark gap therebetween; a secondary winding or coil connected to impress an electromotive force across said spark gap and so mounted as to reciprocate in synchronism with said piston; a primary winding or coil secured in a position which is fixed in relation to said combustion space and in which said secondary coil is brought into inducing relationship with said primary coil as said secondary coil approaches one end of its

reciprocation; and means for passing a high frequency alternating electric current through said primary coil at the instant it is desired to ignite said mixture.

12. In an internal combustion engine having a combustion space into which a combustible gas mixture is periodically delivered: members placed in said combustion space and forming a spark gap upon which an electromotive force may be impressed; a primary winding or coil having relatively few turns; means for passing a high frequency electric discharge through said primary winding; a secondary winding or coil reciprocating with relation to said primary winding to vary the inductive relationship between said windings, said secondary coil consisting of a multiplicity of coils for each coil of said primary winding; and means for impressing across said spark gap any electromotive force induced in said secondary coil.

13. In an internal combustion engine having a combustion space into which a combustible gas mixture is periodically delivered: members placed in said combustion space and forming a spark gap upon which an electromotive force may be impressed; a primary winding or coil having relatively few turns; means for passing a high frequency electric discharge through said primary winding; a secondary winding or coil reciprocating with relation to said primary winding to vary the inductive relationship between said windings, said secondary coil consisting of a multiplicity of coils for each coil of said primary winding; and means for impressing across said spark gap any electromotive force induced in said secondary coil at the instant it is desired to ignite said combustible mixture.

14. In an internal combustion engine having a combustion space into which a combustible gas mixture is periodically delivered: members placed in said combustion space and forming a spark gap upon which an electromotive force may be impressed; a primary winding or coil having relatively few turns; means for passing a high frequency electric discharge through said primary winding; a secondary winding or coil reciprocating with relation to said primary winding to vary the inductive relationship between said windings, said secondary coil consisting of a multiplicity of coils for each coil of said primary winding; means for so reciprocating said secondary winding in synchronism with the piston of said engine; and means for impressing

across said spark gap any electromotive force induced in said secondary coil.

15. In an internal combustion engine having a combustion space into which a combustible gas mixture is periodically delivered: members placed in said combustion space and forming a spark gap upon which an electromotive force may be impressed; a primary winding or coil having relatively few turns; means for passing a high frequency electric discharge through said primary winding; a secondary winding or coil reciprocating with relation to said primary winding to vary the inductive relationship between said windings, said secondary coil consisting of a multiplicity of coils for each coil of said primary winding; means for so reciprocating said secondary winding in synchronism with the piston of said engine; and means for impressing across said spark gap any electromotive force induced in said secondary coil at the instant it is desired to ignite said combustible mixture.

16. In an internal combustion engine having a reciprocating piston and a crankcase oil chamber, the combination of: an electrode mounted on said piston with its discharge head disposed in the combustion chamber of said engine; an extended surface means for transferring heat mounted on said piston and disposed in the crankcase oil chamber of said engine; and heat conducting means connecting said discharge head and said extended surface means.

17. In an internal combustion engine having a reciprocating piston and a crankcase oil chamber, the combination of: an electrode mounted on said piston with its discharge head disposed in the combustion chamber of said engine; heat transferring, laterally extending fins mounted on said electrode and disposed in the crankcase oil chamber of said engine; and insulating material disposed between said electrode and said piston.

18. In an internal combustion engine having a reciprocating piston and a crankcase oil chamber, the combination of: an electrode stem mounted on said piston with its shank projecting in one direction into the combustion chamber of said engine and in the other direction toward the crankcase chamber of said engine; a discharge head mounted on said one projecting end; disk-shaped fins disposed on and transversely of said other end of said shank; and insulating means between said rod and said piston.
